UNITED STATES PATENT OFFICE

109,842

DESIGN FOR A RELIGIOUS THRONE

Chester David Cole, Jamaica Estates, N. Y., assignor to Benziger Brothers, New York, N. Y., a partnership composed of Xavier W. Benziger, Bernard A. Benziger, and Alfred F. Benziger

Application February 15, 1938, Serial No. 75,136

Term of patent 3½ years

To all whom it may concern:

Be it known that I, Chester David Cole, a citizen of the United States, residing at Jamaica Estates, in the county of Queens and State of New York, have invented a new, original, and ornamental Design for a Religious Throne, of which the following is a specification, reference being had to the accompanying drawing, forming part thereof.

I claim:

The ornamental design for a religious throne, as shown.

CHESTER DAVID COLE.
